CLAIM

The ornamental design for an exercise chew with holes as shown and described.

DESCRIPTION

FIG. 1 is a perspective view of the exercise chew with holes showing my new design;

FIG. 2 is a front view thereof;

FIG. 3 is a back view thereof;

FIG. 4 is a top view thereof, with the opposite side being a mirror image; and,

FIG. 5 is a side view thereof.

The broken lines shown in the drawings illustrate portions of the exercise chew with holes that form no part of the claimed design.
